(57) **CLAIM**

We claim the ornamental design for infusion pump with interconnect features, as shown and described.

DESCRIPTION

FIG. 1 is a top rear perspective view of infusion pump with interconnect features according to a first embodiment of the invention.

FIG. 2 is a bottom perspective view of the infusion pump with interconnect features.

FIG. 3 is a front elevation view of the infusion pump with interconnect features.

FIG. 4 is a rear elevation view of the infusion pump with interconnect features.

FIG. 5 is a side elevation view of the infusion pump with interconnect features.

FIG. 6 is another side elevation view of the infusion pump with interconnect features, from the side opposite that in FIG. 5.

FIG. 7 is a top plan view of the infusion pump with interconnect features.

FIG. 8 is a bottom plan view of the infusion pump with interconnect features.

FIG. 9 is a top rear perspective view of infusion pump with interconnect features according to a second embodiment of the invention.

FIG. 10 is a bottom perspective view of the infusion pump with interconnect features according to the second embodiment.

FIG. 11 is a front elevation view of the infusion pump with interconnect features according to the second embodiment.

FIG. 12 is a rear elevation view of the infusion pump with interconnect features according to the second embodiment.

FIG. 13 is a side elevation view of the infusion pump with interconnect features according to the second embodiment.

FIG. 14 is another side elevation view of the infusion pump with interconnect features according to the second embodiment, from the side opposite that in FIG. 13.

(Continued)

FIG. 15 is a top plan view of the infusion pump with interconnect features according to the second embodiment; and,

FIG. 16 is a bottom plan view of the infusion pump with interconnect features according to the second embodiment. In the drawings, the dashed broken lines depict portions of the infusion pump interconnect features that form no part of the claim. The dot-dashed broken lines depict the boundary of the claimed design and form no part of the claim.
